UNITED STATES PATENT OFFICE

105,514

DESIGN FOR AN ELECTRIC CHIME

Evan G. Evans, Cincinnati, Ohio, assignor to
Nutone Chimes Inc., New York, N. Y., a cor-
poration of New York

Application June 4, 1937, Serial No. 69,669

Term of patent 3½ years

To all whom it may concern:

Be it known that I, Evan G. Evans, a citizen
of the United States, residing at Cincinnati, in
the county of Hamilton and State of Ohio, have
invented a new, original, and ornamental De-
sign for Electric Chime, of which the following
is a specification, reference being had to the
accompanying drawing, forming a part thereof.

Figure 1 is a perspective view of the electric
chime showing my new design.

Figure 2 is a side elevation of the same.

I claim:

The ornamental design for an electric chime
as shown.

EVAN G. EVANS.
